UNITED STATES PATENT OFFICE.

GUSTAF E. TORNSJO, OF ST. PAUL, MINNESOTA.

PHOTOGRAPHIC-PRINTING APPARATUS.

1,303,418.

Specification of Letters Patent. Patented May 13, 1919.

Application filed August 19, 1918. Serial No. 250,417.

To all whom it may concern:

Be it known that I, GUSTAF E. TORNSJO, a citizen of the United States, residing at St. Paul, in the county of Ramsey and State of Minnesota, have invented certain new and useful Improvements in Photographic-Printing Apparatus, of which the following is a specification.

My invention relates to photographic printing apparatus. Heretofore, it has been largely the custom with establishments or persons engaged in making photographic prints for amateurs, and other persons as well, to mark each print or to place an identification number on the back thereof where it remains after the prints have been finished. The different orders for prints that come in are usually designated by successive numbers and the number assigned to any particular order is placed on the back of all of the prints belonging to that order. If the numbers are put on in pencil, some additional time is required even when this is done hurriedly and there is always a possibility of error due to placing the wrong number on the print and also on account of numbers being more or less illegible. Furthermore, many persons dislike having marks or numbers on the backs of their prints, especially when these prints are left unmounted. The object of my invention, therefore, is to avoid the above disadvantages by providing an attachment for photographic printing apparatus by means of which one or more edges of the printing paper may be printed with identification characters at the time when the prints are made from the negatives, these characters being produced on the edge of the paper which is trimmed off after the prints have been developed and dried. In carrying out the process the waste edges are trimmed off at the time when the prints are sorted into their proper groups and hence an identification mark on each print is no longer necessary.

The full objects and advantages of my invention will appear in connection with the

detailed description thereof and are particularly pointed out in the claims.

Referring to the drawings which illustrate the application of my invention in one form,—

Figure 1 is a view in perspective of a conventional form of photographic printing apparatus in connection with which my invention is employed. Fig. 2 is an enlarged top plan view of my attachment. Fig. 3 is a view in section on the line 3—3 of Fig. 2. Fig. 4 is a sectional plan view of the letter disk. Fig. 5 is a section on the line 5—5 of Fig. 4.

In the drawings, 12 designates the table of a printing apparatus supported on a stand 14 and having a pivoted pad member 16 adapted to be operated in customary manner to hold the negative 18 (either a plate or a film) and the printing paper 20 in close contact upon a transparent plate 22 set into the table and underneath which are lamps 23 adapted to be switched on and off in the customary manner. These parts are embodied in apparatus of well known construction and need not be described further. Adjacent to adjoining edges of the transparent plate are stops 24 and 26 secured to the table by screws 28. A guide rod 30 is secured to the table adjacent and beyond the stop 24 by attaching members 32 and 34 while a guide rod 36 is secured to the table by an attaching member 38 and the attaching member 34. The guide rod 36 is on the opposite side of the table from the stop 26. The rod 30 serves to guide a slidable cylindrical member 40 having a lug 42 thereon for operating it and having a lug 44 to which is secured a thin masking strip 46 of durable material. This strip is provided with a hole 48 adjacent which are two rotatable disks 50 and 52 secured to the strip by rivets passing through their centers and through the strip. Both disks are provided around their peripheries with the ten numerals from 0 to 9 cut through the material of the disks. These disks are so located relatively to the hole 48 that any number from 1 to 99 may be

made to register with the whole. It is obvious that by a suitable arrangement of disks, larger numbers may be indicated if desired. The rod 36 previously referred to 5 serves to guide a slideable cylindrical member 54 having a lug 56 thereon for operating it and a lug 58 to which is attached a thin masking strip 60 of durable material. This strip is provided with a hole 62 adjacent 10 which is a rotatable disk 64 secured to the strip by a rivet 66 passing through the center of the disk and through the strip. The disk is provided around its periphery with any desired number of the letters of the 15 alphabet, and these letters are cut through the material of the disk, the latter being so located relatively to the hole that any one of the letters may be made to register therewith. By referring to Fig. 2, it will be seen 20 that the distance of the holes 48 and 62 from the inner edges of the strips in which they are cut is the same as the distance of the stops from the adjacent edges of the glass 22. This insures the characters being printed 25 upon the waste edge of the printing paper when the strips are properly positioned. The letters are intended to indicate which particular machine has been used in making the prints while the numbers indicate the 30 particular order or batch that is being printed.

The operation and advantages of my invention will be apparent from the foregoing description. In the use of the apparatus, 35 the negative is placed upon the plate 22 with two of its edges in contact with the stops 24 and 26. The masking strips 46 and 60 preferably lie directly upon the plate 22 so as to be underneath the negatives and they are moved along the guide rods so as to be 40 in proper position relatively to the edges of the negative according to the size of the latter. The disk 64 of course has to be set only once to designate the particular machine. The disks 50 and 52, however, are set 45 to correspond with the number assigned to a particular order or batch each time that the printing of a different order or batch is to be started. The number does not have to be changed until another order or batch 50 is to be printed. The printing paper 20 of the proper size is placed with its sensitized surface in contact with the negative and with two of its edges against the stops 24 and 26 and with the other two edges extending 55 over the holes 48 and 62 as designated by the dot and dash lines 68 in Fig. 2. The pad member 16 is then brought down upon the top of the printing paper and the print is made in the usual manner by means of the lamps 28. The particular letter and number 60 which have been set to register with the holes in the masking strips will be printed photographically upon the waste edge of the

picture. After the prints have been developed and dried, the waste edges thereof are trimmed off, thus removing the identification marks.

I claim:

1. A photographic printing apparatus 70 comprising a support for the negative and the printing paper, a stop adjacent an edge of said support, said stop being adapted for engagement by an edge of said paper, an 75 adjustable masking strip adapted to be positioned underneath the edge of said paper opposite the aforementioned edge thereof, and means carried by said strip for printing identification characters upon the waste 80 edge of said paper.

2. A photographic printing apparatus comprising a support for the negative and printing paper, a pair of stops adjacent two 85 adjoining edges of said support respectively, 85 said stops being adapted for engagement by adjoining edges of said paper, a pair of adjustable masking strips adapted to be positioned underneath the edges of said paper respectively opposite the aforementioned 90 edges thereof, and means carried by each of said strips for printing identification characters upon the waste edges of said paper.

3. A photographic printing apparatus 95 comprising a support for the negative and the printing paper, a stop adjacent an edge of said support, said stop being adapted for engagement by an edge of said paper, an adjustable masking strip adapted to be positioned underneath the edge of said paper 100 opposite the aforementioned edge thereof, said strip being provided with a hole and a movable member having a plurality of characters cut therethrough, said member being adapted for movement whereby any- 105 one of said characters may be brought into register with said hole.

4. A photographic printing apparatus comprising a support for the negative and the printing paper, a stop adjacent an edge 110 of said support, said stop being adapted for engagement by an edge of said paper, an adjustable masking strip adapted to be positioned underneath the edge of said paper opposite the aforementioned edge thereof, 115 said strip being provided with a hole and a rotatable disk having a plurality of characters cut therethrough and extending around the periphery thereof, said disk being adapted for rotation whereby anyone 120 of said characters may be brought into register with said hole.

5. A photographic printing apparatus comprising a support for the negative and the printing paper, a pair of stops adjacent 125 two adjoining edges of said support respectively, said stops being adapted for engagement by adjoining edges of said paper, a pair of guide rods adjacent two adjoining

edges of said support respectively, an adjustable masking strip slidably mounted on each of said guide rods, said strips being adapted to be positioned underneath the edges of said paper respectively opposite the aforementioned edges thereof, and means

carried by each of said strips for printing identification characters upon the waste edges of said paper.

In testimony whereof I hereunto affix my 10
signature.

GUSTAF E. TURNSJO.
